(57) **CLAIM**

The ornamental design of a land clearing tool, as shown and described.

DESCRIPTION

FIG. 1 an isometric view of a land clearing tool;

FIG. 2 is a rear isometric view thereof;

FIG. 3 is a right side view thereof;

FIG. 4 is a left side view thereof;

FIG. 5 is a top view thereof;

FIG. 6 is a bottom view thereof;

FIG. 7 is a front view thereof; and,

FIG. 8 is a back view thereof.

The contour lines in FIGS. 1-8 represent contour and not surface ornamentation.
